(57) **CLAIM**

The ornamental design for a construction clip, as shown and described.

DESCRIPTION

FIG. 1 is a front perspective view of a construction clip, showing our new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof;

FIG. 7 is a front perspective view thereof, shown in a state of use;

FIG. 8 is an enlarged perspective view of the portion of FIG. 1 inside the dash-dot-dot broken line circle indicated by the reference number 8;

FIG. 9 is an enlarged perspective view of the portion of FIG. 1 inside the dash-dot-dot broken line circle indicated by the reference number 9;

FIG. 10 is an enlarged left side view of the portion of FIG. 6 inside the dash-dot-dot broken line circle indicated by the reference number 10; and,

FIG. 11 is an enlarged left side view of the portion of FIG. 6 inside the dash-dot-dot broken line circle indicated by the reference number 11.

The even-length broken lines shown in the drawings represent portions of the construction clip that form no part of the claimed design. The dash-dot-dot broken lines depict areas of enlargement in FIGS. 1 and 6 and the boundaries of the corresponding enlarged views in FIGS. 8, 9, 10 and 11. The dash-dot broken lines shown inside the dash-dot-dot broken line circles shown in FIGS. 1, 6, 8, 9, 10 and 11 depict the bounds of the claim and form no part of the claimed design.
